UNITED STATES PATENT OFFICE.

OTTO C. HOFFMANN, OF BUFFALO, NEW YORK, ASSIGNOR TO THE FUSE WIRE & MANUFACTURING COMPANY, OF BUFFALO, NEW YORK, A CORPORATION OF NEW YORK.

ELECTRIC FUSE.

No. 821,873.

Specification of Letters Patent.

Patented May 29, 1906.

Application filed April 25, 1904. Serial No. 204,707.

To all whom it may concern:

Be it known that I, OTTO C. HOFFMANN, a citizen of the United States, residing at Buffalo, in the county of Erie and State of New York, have invented new and useful Improvements in Electric Fuses, of which the following is a specification.

My invention relates to fuses for electrical circuits; and it relates more particularly to 10 that portion of the fuse which is employed as an indicator and also to the form and design of the fuse thus employed, together with its location and surroundings, all of which coöperate to bring about a desirable function in 15 connection with the article as a whole.

It also consists in a new article of manufacture in which there is associated with the main fuse an auxiliary fuse having peculiarities and structure herein specified, and particularly pointed out in the claims forming a 20 part hereof, the same being illustrated in the drawings, in which—

Figure 1 is a longitudinal section of the fuse. Fig. 2 is an alternate form of the fuse; 25 Fig. 3, one view of the indicator; Figs. 4 and 5, details of the indicating-fuse.

Like letters indicate similar parts throughout.

Referring now to the drawings, we observe 30 that terminals T T (shown in Fig. 1 in the form of blocks and in Fig. 2 in the form of metallic caps) are suitably supported upon an insulating material A and may be protected by a covering, preferably of insulating 35 material, or shield a. These terminals are electrically connected by a plurality of fusible conductors which traverse two paths in connecting the terminals, one or more passing practically in a straight line, as seen at B, 40 whereas another, and preferably one of less conductivity, C, passes to the exterior of the shield or case a for a short distance of its length. At the point where the conductor C passes to the exterior of the case, the case is 45 preferably depressed at this point, as indicated at D, for the better protection of the fuse and for the further purpose of better providing a background for the fuse, which may be colored to contrast not only with the case 50 a itself, but with the color of the fuse C. It will be further observed that this fuse C may consist of a small cylindrical wire, as shown in Fig. 4, which has been flattened out or otherwise deformed at a predetermined point, (indicated by e,) and this deformation 55 is carried to such an extent as to actually reduce the sectional area at this point. It has been found in practice that even this reduction of sectional area must be carried sufficiently far so that the extra radiating-surface 60 provided in increase of surface will be overcome and the fuse will blow or rupture along this particular section of the wire e. As a matter of fact this conductor C will perform all its functions if it is simply the merest 65 hair-like conductor, and it is found preferable to make it of very slight conductivity, inasmuch as such conductor will at once eliminate all necessary recalibration of the standard 70 fuses B; but the difficulty arises that it cannot be seen or readily detected, and therefore is almost useless as an indicator. Such conductors have heretofore been employed, but rendered practical only when employed in connection with some combustible or explosive 75 substance which it is desired to avoid, especially in any device designed to protect against fire loss, as is the case with the enclosed fuse. To avoid the use of these combustibles or explosives, I have discovered 80 that an extremely-small conductor, not much larger than a hair, may be employed and the wire rendered visible by the mere act of flattening it out to a degree which will insure its 85 rupture and fusing at this particular point, as illustrated at e in the figures. To render its action more certain and to be able to detect the indicator more readily, it is found expedient to place it within the depression, 90 as has been explained, providing the surface of the depression with a color which may be of fireproof material and a backing which will discolor upon the normal rupture or blowing of the fuse, and to still further increase this 95 protective factor, as well as the discoloration due to blowing, it is found that a varnish of a suitable material will still further increase the discoloration. It will render the parts more 100 observable through the magnifying effect and transparent qualities of the varnish, this latter effect being one similar to the magnifying of the mercury column within a thermometer. Among such varnishes may be mentioned the 105 cellulosic lacquers and the gums, such as transparent shellac. The varnish also acts as a cement to tightly hold the indicating-

fuse in position. In Figs. 1 and 2 it will be observed that the main conductor or conductors B is shorter than the entire length between the terminals T and that a supplementary conductor B' B' is employed to complete the circuit. While it is true that this conductor is of larger area than B, it will be seen at the same time it is of larger cross-section, and therefore a better conductor, whereas the enlarged area e of the conductor C is one which produces a small cross-section and is therefore of less conductivity.

Having thus described the invention, its operation will be apparent from the previous statement.

The function of the indicator-conductor C is to give the indication, which in this instance is visual, that the main conductor or conductors B have been destroyed or open-circuited. The visual indication in the present instance consists not only of the rupture and destruction of the part e of the conductor C, but supplementary to this act and brought into existence thereby is a very considerable discoloration of the backing and surrounding surface D, the combined action being such as to bring about a condition instantly observable at a distance and one found in practice to be extremely satisfactory.

It is not intended that this invention should be limited to the exact details illustrated and described, as equivalent and other devices may be used to fulfil the functions.

It is further understood, while the details may be employed in substantially the relation indicated, that some of the parts may be omitted and the remaining ones employed either alone or with natural and operative substitution for those omitted, and the invention extends to such use.

I claim—

1. A fuse for electric circuits consisting of an integral cylindrical conductor flattened to a thin sheet-like section and thus presenting the greatest area at its fusing-point.

2. A fuse for electric circuits consisting of an integral conductor presenting the greatest area and a thinner section at a predetermined point along its length which is to become its fusing-point.

3. A fuse for electric circuits consisting of an integral cylindrical conductor presenting the greatest area and the smallest cross-section at a predetermined point along its length which is to become its fusing-point.

4. In an inclosed fuse, a casing, an indicator for the fuse consisting of a fine difficultly-visible wire flattened and greatly extended as to area so as to be visible at a predetermined point in its length, and a depression extending partially through the wall of the casing in which the indicator lies, for the purpose set forth.

5. In an inclosed fuse an indicator consisting of a fusible conductor of small size passing from the interior to the exterior of the inclosure flattened so as to be visible at a point outside the inclosure, and a backing for the fuse depressed below the general surface of the surrounding material against which the flattened part lies, the walls of the depression of different color than the surroundings.

6. In an inclosed fuse an indicator consisting of a fusible conductor of small size flattened so as to be visible at a predetermined point in its length, a backing for the fuse, the fuse lying upon the backing and a varnish for covering the fuse.

7. In an inclosed fuse an indicator consisting of a fusible conductor of small size, a discolored backing, the fuse lying upon the backing and a discolored varnish covering the fuse.

In testimony whereof I have hereunto set my hand in presence of two subscribing witnesses.

OTTO C. HOFFMANN.
